UNITED STATES PATENT OFFICE.

JOHN F. O'CONNOR, OF CHICAGO, ILLINOIS, ASSIGNOR TO WILLIAM H. MINER, OF CHAZY, NEW YORK.

SELF-ALINING SIDE BEARING.

1,357,812.

Specification of Letters Patent.

Patented Nov. 2, 1920.

Application filed September 25, 1919. Serial No. 326,126.

To all whom it may concern:

Be it known that I, JOHN F. O'CONNOR, a citizen of the United States, residing at Chicago, in the county of Cook and State of Illinois, have invented a certain new and useful Improvement in Self-Alining Side Bearings, of which the following is a full, clear, concise, and exact description, reference being had to the accompanying drawings, forming a part of this specification.

This invention relates to improvements in self-alining side bearings.

As is well known, in the art of side bearings for railway cars it is desirable to provide means permitting the adjustment or alinement of the anti-friction element so as to at all times insure line contacts between the anti-friction element and the bearing surfaces carried by the body and truck bolsters. The angular relation of these bearing surfaces of the body and truck bolsters varies during service, the variation being caused sometimes by wearing of the parts and at other times by distortion of the bolsters. Heretofore, adjustment or alinement of the character above indicated has been accomplished by mounting the anti-friction element in a cradle or on a corresponding additional element, the cradle or said element being rockably mounted, or pivotally mounted, to permit the adjustment necessary, the cradle or other anti-friction element carrying member is, in turn, suitably mounted within or on a base casting or other retaining member directly secured to the bolster,

The object of my invention is to provide a side bearing which is automatically adjustable or self-alining to accommodate itself to variations in the angles between the bearing surfaces of the body and truck bolsters of railway cars, which side bearing eliminates the use of a cradle or equivalent member heretofore found necessary.

More specifically, the object of my invention is to provide an anti-friction element suitable for use in side bearings, which element contains within itself the means for accomplishing the alinement or adjustment desired in railway side bearings.

The invention, furthermore, consists in improvements in the parts and devices and in the novel combinations of the parts and devices herein shown, described and made the subject matter of claims.

In the drawing forming a part of this specification, Figure 1 is a vertical sectional view taken parallel to the center sill of a railway car through the ends of the body and truck bolsters showing my improvements in connection therewith. Fig. 2 is an end elevation of the improved anti-friction element. Fig. 3 is a side elevation of the anti-friction element. And Fig. 4 is a vertical transverse sectional view taken substantially on the line 4—4 of Fig. 3.

In said drawing, 10 indicates the under side of a body bolster of a railway car and 11 the upper side of an opposed truck bolster, it being understood that the bolsters are pivotally connected at their centers by a king pin or otherwise in a well-known manner. I have shown my improved bearing as applied to the truck bolster, and, as shown, the bearing comprises, broadly, two elements, a housing or retaining or base casting A and an anti-friction element proper B.

The housing A, as shown, is provided with spaced parallel side walls 12—12, curved end walls 13—13, a bottom bearing wall 14 and perforated corner lugs 15 by which it is riveted or otherwise secured to the truck bolster. The side walls may be cut away, as indicated at 16, to permit dirt and other foreign matter being washed out.

The anti-friction element B, as shown, comprises two parts or sections designated B¹ and B². The parts B¹ and B² are pivotally connected in the manner hereinafter described by a rivet 17, as shown most clearly in Fig. 4.

The element B, considered as an entirety, is of substantially triangular formation in end elevation, the sides of the triangle being formed by curved surfaces. As shown, the element B has a bottom curved bearing surface 18 adapted to roll along the bottom wall 14 of the housing A and an upper concentric curved bearing surface 19 of shorter radius, the bearing surface 19 being adapted to coöperate with the adjacent bearing surface on the body bolster 10. The other surfaces of the anti-friction element B are also formed in sets of curved concentric bearing surfaces, as will be understood. With this construction, it is evident that the anti-friction element is self-centering under the influence of gravity in the manner of a rocker. To prevent bodily displacement or shifting of the element B with respect to

the housing A, I preferably provide a plurality of teeth 20 in the bottom of the housing A, which coöperate with corresponding recesses 21 in the lower part of the element 5 B, the teeth and recesses obviously maintaining a definite relation between the element B and the housing.

As hereinbefore stated, the sections B¹ and B² are pivotally connected by the rivet 10 17. This pivotal connection extends transversely of, or at right angles to, the rolling axis of the element B; or, stated in another manner, the axis of the pivotal connection between the sections B¹ and B² extends at 15 right angles to the lines of bearing contact between the antifriction element and the bearing surfaces of the bolsters. The details of the construction of the pivotal connection between sections B¹ and B² may be 20 varied, the form which I have shown consisting of an upstanding central post 22 on the lower section B² and a pair of depending arms 23—23 on the upper section B¹ which straddle the post 22. Perforations are 25 formed in the post and arms to accommodate the rivet 17, as clearly indicated, and a small amount of clearance is left between the parts to provide for easy relative adjustment.

30 Referring to Fig. 3, it will be noted that the adjacent surfaces 24 and 25 of the sections B¹ and B², respectively, are beveled away from the rivet 17 so that the sections B¹ and B² are relatively adjustable about 35 the axis of the rivet 17 within the limits desired. In this way, it is evident that the line of bearing contact between the lower section B² and its corresponding bearing on the truck bolster and the line of bearing contact between the upper surface of the section B¹ and its opposed bearing surface of 40 the body bolster can always be obtained, even though the angle changes, so long as the change is within the limits provided 45 for by the adjustments between sections B¹ and B².

In the preceding description, it is evident that I have entirely eliminated the usual cradle or rocker found in side bearings of 50 the adjustable or alining type, thereby reducing first cost and also the cost of maintenance, and, in addition, I have provided a self-alining side bearing which automatically returns to its central normal position 55 after each actuation under the influence of gravity and without the aid of any extraneous parts—such as springs or the like.

I claim:

1. In a side bearing, the combination with 60 a retaining member adapted to be secured to a bolster, of an anti-friction element arranged to roll bodily back and forth therein, said anti-friction element having one section thereof relatively adjustable to another

section thereof about an axis extending at 65 right angles to the line of bodily movement of said element, each of said sections having a bearing surface.

2. In an anti-friction bearing adapted to be applied between body and truck bolsters 70 of a railway car, the combination with a retaining member adapted to be secured to one of said bolsters, of an anti-friction element arranged to roll bodily back and forth within said member, said anti-friction element 75 comprising a plurality of sections, said sections being relatively adjustable for a limited amount to thereby accommodate the bearing surfaces of said element to varying angles between the bearing surfaces of 80 the bolsters.

3. In a side bearing, the combination with a retaining member adapted to be secured to a bolster, of a gravity self-centering anti-friction element of rocker form associated 85 with said retaining member, said anti-friction element comprising an upper and a lower section, the sections being relatively adjustable independently of the retaining member about an axis extending at right angles to the axis of rolling movement of said 90 rocker element.

4. In a side bearing for railway cars, the combination with a housing adapted to be secured to a bolster, of a sectional, self-aligning, gravity self-centering anti-friction element adapted to roll bodily and disposed within said housing, and coöperating means on said element and housing for maintaining a definite relation between said element 100 and housing and to prevent bodily shifting of the element with respect to the housing.

5. As an article of manufacture, an anti-friction element adapted for use in side bearings, said element having concentric curved 105 upper and lower bearing surfaces adapting it to roll bodily, said element being comprised of an upper section and a lower section relatively adjustable about an axis extending at right angles to the axis of the 110 bearing surfaces.

6. As an article of manufacture, a rocker adapted for use in a side bearing, said rocker having a curved lower bearing surface and an upper curved bearing surface, 115 the rocker being weighted so as to be self-returning on said lower bearing surface, said upper and lower bearing surfaces being formed on separate sections of the rocker, the sections being relatively adjustable to 120 permit variations of the angular relation of the upper and lower bearing surfaces.

7. As an article of manufacture, an anti-friction rocker adapted for side bearings, said rocker consisting of two sections pivotally connected, said sections having bearing surfaces extending at right angles to the axis of the pivotal connection, the rocker, as 125

an entirety, being of substantially triangular outline in end elevation and self-returning under the influence of gravity.

8. In a side bearing for railway cars, the combination with a hollow base casting adapted to be secured to a truck bolster, said base casting having side walls, end walls and a bottom bearing wall, of an anti-friction rocker disposed within said base casting,
5 said rocker being of substantially triangular form in end elevation, the upper and lower bearing surfaces of the rocker being

concentric but of different radii, said rocker being formed in two sections pivotally connected about an axis extending at right angles to the axis of the rocker as an entirety, and coöperating means on the lower section of the rocker and the base casting arranged to prevent bodily shifting of the rocker with respect to the base casting. 15

In witness that I claim the foregoing I have hereunto subscribed my name this 8th day of Sept., 1919.

JOHN F. O'CONNOR.
